UNITED STATES PATENT OFFICE

2,533,220

FOLDABLE BOAT

Austin S. Carter, Chelan, Wash.

Application December 9, 1947, Serial No. 790,647

4 Claims. (Cl. 9—2)

1

This invention relates to boats and it is one object of the invention to provide a boat formed with sections so constructed and so connected with each other that the sections may be moved from an extended position in which they form a bow section, a stern section and a mid-section to a folded position in which the bow section is enclosed between the mid-section and the stern section and the boat thus reduced to a compact mass and may be readily transported from one place to another.

Another object of the invention is to provide a boat having its sections so constructed that when they are in the extended position each section will be water tight and water thus prevented from entering and filling the boat while it is in use.

Another object of the invention is to so connect the sections that when the boat is being folded the bow section may be shifted upwardly and then rearwardly and downwardly to a position at rest upon the mid-section, the rear section being then swung upwardly and forwardly about hinges at its front end deposited in an inverted position in covering relation to the front section where it will very effectively cover and shield the bow section from damage by weather or by articles which might otherwise drop into the folded bow section.

Another object of the invention is to provide a cable for bracing the sections when in the extended position for use, said cable extending along the keel of the boat and having its ends connected with securing members carried by the stern section and the bow section, the securing member of the bow section being a lever pivoted for movement into and out of position for exerting tightening pull upon the cable.

Another object of the invention is to mount the cable that while its front end will be released when the boat is folded it will remain in engagement with the other sections and will be readily accessible when the sections are to be secured in an extended position.

Another object of the invention is to provide a foldable boat which is of simplified construction, very strong, and capable of being easily folded or have its sections moved to an extended position for use of the boat.

A practical embodiment of the invention is illustrated in the accompanying drawings wherein:

Fig. 1 is a side elevation of the improved foldable boat.

Fig. 2 is a top plan view of the boat, portions of the deck boards being removed.

2

Fig. 3 is a sectional view taken longitudinally through the boat, the dotted lines illustrating the manner in which the bow section is moved to an extended or folded position.

5 Fig. 4 is a sectional view upon an enlarged scale taken longitudinally through the boat.

Fig. 5 is a transverse sectional view of the boat.

Fig. 6 is a side view showing the boat folded.

This improved boat may be formed of wood, metal, or other suitable materials and has a bow section 1, a stern section 2, and a mid-section 3. At its front end the front section or bow section 1 has the usual stem 4 and at its rear end the rear section or stern section 2 has the usual counter 5. A keel extends longitudinally of the boat midway the width thereof and is formed in sections so that each section of the boat carries a portion of the keel. There have also been provided cross beams 7, certain ones of which are 10 located at ends of the mid-section and at the rear end of the bow-section and the front end of the stern section for abutting engagement with each other when the sections are in the extended position. The cross beams at the abutting ends of the sections form walls for excluding water and preventing the boat from being filled with water when it is in use and, of course, extend upwardly above the water line of the boat. Decks 8 have been provided for the three sections 15 and the stern section has also been shown formed with cock pits 9 but it will be understood that the decks and the cock pits may be omitted if so desired.

In order to mount the front section 1 for 35 movement from an extended position in which it projects forwardly from the front end of the mid-section there have been provided arms or hinge bars 10 which extend longitudinally of the boat and have their rear ends pivoted to

40 blocks 11 secured upon the gunwales at opposite sides of the midsection of the boat. The front ends of the bars 10 are extended downwardly to form ears 12 pivoted to pins 14 in blocks 13 at opposite sides of the bow section of the boat and 45 since the blocks 13 are mounted against outer side faces of the sides of bow section, this section will be located between the bars and may be lifted as the bars are swung upwardly and rearwardly. During this movement of the bars the bow section first moves upwardly and then rearwardly and downwardly to a position at rest within the midsection without being inverted.

50 Chains 15 which are secured at their ends to the bars and to outer faces of opposite sides of the bow section assist in supporting the rear end of the bow section and preventing excessive side

play thereof as it is moved to a retracted position or an extended position and in order to brace the bow section against transverse play when in the extended position there has been provided an elongated cleat 16 mounted upon the deck of the bow section and projecting rearwardly therefrom for engagement in the half-round saddle or seat 17 secured upon the deck of the midsection.

The stern section 2 pivoted to the rear end of the midsection by hinges 18 is secured upon the gunwales of this section and is swung upwardly and forwardly to a folded or retracted position in which it rests in an inverted position upon the retracted bow section. This is shown in Figure 6, and referring to this figure it will be seen that since the bow section is disposed between the midsection and the stern section and the stern section is inverted the bow section will be enclosed by the midsection and the stern section and prevented from being exposed to rain.

The three sections must be firmly held in position to form a serviceable boat when the bow section and the stern sections are extended, and in order to do so there has been provided a cable 19, formed of wire or other suitable material, and this cable extends along the keel of the boat with portions passed through eyes 20 which project downwardly from the keel. A plate 21 is pivoted to a bracket 22 projecting rearwardly from the counter 5 and the rear end of the cable is connected with the lower end of plate 21 by a turn buckle 23, a ring 24 being carried by the upper end of the plate and serving as a hand hold which is grasped when the stern section is to be swung forwardly to the folded or retracted position. At its front end the cable carries a clevis 25 provided with a cross pin 26, the clevis being of such size that a lever 27 pivoted to a bracket 28 near the upper end of the stem 4 may be passed through the clevis and the pin engaged with the bill 29 of the lever. After the bow and stern sections are in the extended position the lever is passed through the clevis and as the lever is swung upwardly to the raised position shown in Figure 4 pull will be exerted to tighten the cable and firmly bind the three sections in the extended position. Since the lever passes a dead center before reaching its fully raised position it will not accidentally move to a releasing position. If it is found that the cable is not tight enough the lever is swung downwardly to release the cable from pull, the turn buckle tightened, and the lever again swung upwardly to the raised position and if the turn buckle has been sufficiently tightened proper pull will be exerted upon the cable. When the boat is to be folded the lever is swung downwardly to release the cable and allow the bow and stern sections to be moved to their retracted or folded positions, but since the cable passes through the guides or eyes 20 it will be held longitudinally of the three sections and may be readily grasped and its clevis engaged with the lever when the boat is to be again used.

Having thus described the invention, what is claimed is:

1. A foldable boat comprising a bow section, a stern section, a midsection, said sections having abutting ends provided with cross walls extending above the water line of the boat and serving to exclude water from the boat during use of the boat, hinge bars extending longitudinally of the boat, blocks carried by the bow section and the midsection at opposite sides thereof and to which front and rear ends of the hinge bars are pivoted to mount the said bars for vertical swing-

ing movement and allow the bow section to be shifted upwardly and then rearwardly and downwardly to a retracted position upon the midsection while remaining upright, hinges pivotally connecting opposite sides of the stern section with the rear end of the midsection and mounting the stern section for vertical swinging movement from an extended position to a retracted and inverted position upon the retracted bow section and together with the midsection enclosing the bow section, a cable extending longitudinally of said sections along the keel of the boat and having its rear end secured at the rear end of the stern section, a clevis at the front end of said cable, a cross pin carried by said clevis, and a lever pivoted to the stem of the bow section for vertical swinging movement and having a bill for engaging the pin when the lever is passed through the clevis and exerting pull to tighten the cable when the lever is swung upwardly to a set position.

2. A foldable boat comprising bow and stern sections and a midsection disposed in end to end relation to each other and having abutting ends provided with water-tight closures, the bow section having a stem at its front end and the stern section having a counter at its rear end, arms having rear ends pivoted at opposite sides of the midsection in spaced relation to front and rear ends thereof and having their front ends formed with downwardly extending ears pivoted to opposite sides of the bow section near the rear end thereof and mounting the bow section for movement upwardly and then rearwardly and downwardly from an extended position to a retracted position at rest upon the midsection, hinges pivotally connecting the front end of the stern section with the rear end of the midsection and mounting the stern for swinging movement upwardly and forwardly to an inverted position over the midsection at rest upon the retracted bow section in covering relation thereto, a bracket carried by and extending rearwardly from counter midway the length of the upper edge thereof, a plate pivoted to said bracket in a vertical position, a ring at the upper end of said plate constituting a hand hold, a bracket projecting forwardly from the upper end portion of the stem of said bow section, a lever pivoted to the last mentioned bracket for vertical swinging movement from a lowered position to a raised position and provided with a bill, guides extending downwardly from the said sections and spaced from each other along the keel portion of the boat, a cable threaded through said guides and having its rear portion extending upwardly at the rear end of the stern section and its forward portion extending upwardly along the stem of the bow section, a turn buckle connecting the rear end of said cable with the lower end of said plate, a clevis at the front end of said cable through which said lever is adapted to be passed, and a cross pin carried by said clevis for engagement with the bill of the lever whereby upon swinging the lever upwardly to a raised position pull will be exerted to tighten the cable and brace the said sections against movement towards a retracted position when in an extended position.

3. A foldable boat comprising bow and stern sections and a midsection disposed in end to end engagement with each other when in an extended position, water-tight closures for abutting ends of said sections, bars extending longitudinally of the boat and having their rear ends pivoted to 70 75 the midsection and their front ends pivoted to

the bow section and mounting the bow section for movement upwardly and rearwardly and then downwardly to a retracted position at rest upon the midsection; hinges mounted upon gunwales of abutting ends of the midsection and the stern section and pivotally mounting the stern section for swinging movement upwardly and forwardly to a retracted and inverted position over the midsection in covering and enclosing relation to the retracted bow section, a cable extending along bottoms of said sections longitudinally of the boat and secured at one end to one of the end sections of the boat, a clevis at the other end of said cable, and a lever pivotally mounted upon the other end sections of the boat for vertical swinging movement in position for passing through said clevis and exerting pull when swung upwardly to tighten the cable and thereby brace the said end sections of the boat against movement towards a retracted position.

4. A foldable boat comprising bow and stern sections and a midsection disposed in end to end engagement with each other when in an extended position, water-tight closures for abutting ends of said sections, bars extending longitudinally of the boat and having their rear ends pivoted to the midsection and their front ends pivoted to the bow section and mounting the bow section for movement upwardly and rearwardly

and then downwardly to a retracted position at rest upon the midsection, hinges mounted at sides of abutting ends of the stern section and the midsection and pivotally mounting the stern section for vertical swinging movement upwardly and forwardly to a retracted and inverted position over the midsection in covering and enclosing relation to the retracted bow section, and means for releasably securing said bow section and said stern section in the extended positions in which they have abutting engagement with the midsection.
